UNITED STATES PATENT OFFICE.

JOSEPH MATTHEWS, OF NEWBURYPORT, MASSACHUSETTS, ASSIGNOR OF ONE-HALF TO
WILLIAM H. HASTINGS, OF MALDEN, MASSACHUSETTS.

GREASE-CUP.

1,156,302.

Specification of Letters Patent. Patented Oct. 12, 1915.

Application filed March 18, 1915. Serial No. 15,986.

To all whom it may concern:

Be it known that I, JOSEPH MATTHEWS, a citizen of the United States of America, and a resident of Newburyport, in the 5 county of Essex and State of Massachusetts, have invented certain new and useful Improvements in Grease-Cups, of which the following is a specification.

This invention relates to grease cups, and 10 has for its object the production of a cup of this character that is adapted for use either on a stationary part or a rotatable member such as the hub of a pulley.

The invention consists in certain novel 15 features of construction and arrangement of parts which will be fully understood by reference to the description of the drawings and to the claims hereinafter given.

Of the drawings: Figure 1 represents an 20 elevation of the hub of a pulley with a grease cup embodying the principles of the present invention applied thereto. Fig. 2 represents a vertical section of the grease cup adjusted for use on a revolute member. 25 Fig. 3 represents a similar section of the same grease cup adjusted for use on a stationary part, and Fig. 4 represents a transverse section of the same, the cutting plane being on line 4—4 on Fig. 3.

Similar characters designate like parts 30 throughout the several figures of the drawings.

In the drawings, 10 is the hub of a pulley or other revolute member, the bearing surface of which it is desired to lubricate. 35 Threaded to an opening 11 through the hub is the tubular member 12, the outer end of which is closed as indicated at 13 in Figs. 2 and 3. A closing cap 14 is threaded or 40 otherwise secured to the outer end of said tubular member 12, this member being provided with a discharge opening 15 adjacent to the inner face of said closing cap 14. The opening 15 extends through the side 45 wall of said tubular member 12 from the interior bore thereof to its periphery and said opening is adapted to be closed or partially closed by the sleeve or collar 16 threaded to said tubular member 12 and adjustable 50 lengthwise thereon to regulate the discharge through said opening. Surrounding and freely movable lengthwise of said tubular member 12 is a cup-shaped member 17, the open end of which is adapted to be closed by

the cap 14 which loosely fits the interior 55 thereof.

The cup 17 is adapted to contain a heavy grease and as the bottom thereof is moved toward the cap 14 the grease will be forced through the opening 15, the amount of 60 grease forced through depending on the position of the sleeve 16. The grease passing through the opening 15 will enter the interior bore 18 of the member 12, and will pass therethrough or be forced therethrough 65 to the surface to be lubricated. The inner end of the tubular member 12 is threaded to the hub 10 or other member either revolute or stationary which has a bearing surface which it is desired to lubricate. When 70 the tubular member 12 is fixed in a stationary member the nut 19 threaded to said tubular member is adjusted so that the cup 17 is moved outwardly until the cap 14 is within the open end thereof. As more grease is 75 required, the nut 19 is adjusted to force the cup 17 farther outwardly, thereby causing the grease in said cup to be forced through the opening 15. It is obvious that by adjusting the sleeve 16 the amount of grease to 80 be discharged may be predetermined, and that when the sleeve 16 has been once adjusted it cannot be tampered with, inasmuch as it is inclosed within the cup 17. When the member 12 is secured to a revolute hub 85 10, the nut 19 is moved farther away from the cap 14 into a position such as shown in Fig. 2, with the end thereof a short distance from the cap 14. As soon as the hub begins to revolve, the centrifugal action on 90 the cup 17 will move it outwardly as indicated in dotted lines in Fig. 2, and the grease will be forced through the opening 15 in the manner hereinbefore described. The outward movement of the cup 17 is limited by 95 the compression of the grease, and as this is used the cup will move farther outwardly. A steady and uniform supply of grease is thus automatically insured at all times. One great advantage of the cup is the fact 100 that it may be used in any place either on a stationary part or a movable member. The supply of grease may be predetermined, and when the regulating sleeve 16 has been once adjusted it cannot be tampered with 105 easily, or its position accidentally changed, owing to the fact that it is entirely inclosed and submerged in the grease. The nut 19

is of slightly greater diameter than the cup 17, thereby making it easy to adjust.

It is self-evident that the parts of the grease cup are reduced to a minimum, and 5 are of such simple construction as to make it very inexpensive to manufacture.

It is believed that the operation and many advantages of this grease cup will be fully apparent from the foregoing description.

10 Having thus described my invention, I claim:

1. In a device of the class described, the combination of a tubular member closed at its outer end and having an opening there- 15 through adjacent said closed end, said member being of the same diameter throughout and having a helical thread from end to end; a cap secured to said closed end; a cup-shaped member surrounding said tubular member and movable relatively thereto and a member threaded to the inner end of said tubular member.

2. In a device of the class described, the combination of a threaded tubular member 25 closed at its outer end and having an opening therethrough adjacent said closed end; a sleeve on said tubular member and adjustable thereon to regulate the discharge through said opening; a cap secured to said 30 closed end; and a cup-shaped member surrounding said tubular member and movable relatively thereto.

3. In a device of the class described, the combination of a threaded tubular member 35 closed at its outer end and having an opening therethrough adjacent said closed end; a sleeve threaded to said tubular member and adjustable thereon to regulate the discharge through said opening; a cap secured 40 to said closed end, and a cup-shaped member surrounding said tubular member and movable relatively thereto.

4. In a device of the class described, the combination of a threaded tubular member 45 closed at its outer end and having an opening therethrough adjacent said closed end; a cap secured to said closed end; and a cup-shaped member surrounding said tubular member and movable relatively thereto; and 50 a nut on said tubular member adapted to control the movement in one direction of said cup-shaped member relatively to said cap.

5. In a device of the class described, the 55 combination of a tubular member closed at its outer end and having a side opening therein adjacent its closed end; a cap secured to the closed end thereof; a cup-shaped member on said tubular member 60 freely movably lengthwise thereof; and ad-

justable means on said tubular member for limiting the inward movement of said cup-shaped member.

6. In a device of the class described, the combination of a tubular member closed at 65 its outer end and having a side opening therein adjacent its closed end; a cap secured to the closed end thereof; a cup-shaped member on said tubular member freely movable lengthwise thereof; adjustable means on said tubular member for limiting the inward movement of said cup-shaped member; and means for regulating the discharge through said side opening.

7. In a device of the class described, the 75 combination of a tubular member closed at its outer end and provided with a cap and an opening therein adjacent the inner face of said cap; a cup-shaped member surrounding said tubular member and movable 80 lengthwise thereof; and means within said cup-shaped member for controlling the discharge through said opening.

8. In a device of the class described, the combination of a tubular member closed at 85 its outer end and provided with a cap and an opening therein adjacent the inner face of said cap; a cup-shaped member surrounding said tubular member and movable 90 lengthwise thereof; and means mounted on said tubular member within said cup-shaped member for controlling the discharge through said opening.

9. In a device of the class described, the combination of a tubular member closed at 95 its outer end and having a cap on its outer end and an opening therein adjacent the inner face of said cap; a cup-shaped member surrounding and freely movable lengthwise of said tubular member; and means mounted 100 on the inner end of said tubular member for forcing said cup-shaped member toward said cap.

10. In a device of the class described, the combination of a tubular member closed at 105 its outer end and having a cap on its outer end and an opening therein adjacent the inner face of said cap; a cup-shaped member surrounding and freely movable length- 110 wise of said tubular member; and means threaded to the inner end of said tubular member for forcing said cup-shaped member toward said cap.

Signed by me at Boston, Massachusetts, this 15th day of March, 1915.

JOSEPH MATTHEWS.
